WIRE FABRIC AND METHOD OF MAKING
THE SAME

Otto Carl Scherfel, Haddon Heights, N. J., assignor to Audubon Wire Cloth Corporation, Philadelphia, Pa., a corporation of New Jersey

Application April 29, 1936, Serial No. 76,922

8 Claims. (Cl. 245—6)

My invention relates to belt structure of wire fabric comprising helically coiled wires arranged in interlaced and/or interconnected condition throughout the entire extent of the fabric; said 5 helically coiled wires lying transversely of the fabric when employed as a belt structure, and it comprises an improved form of wire belt fabric in which cross rods or wires are associated with the interconnected bights of the helically coiled wires 10 for the purpose of reinforcing the fabric; each of said cross rods or wires having at one end a bent portion which lies within the marginal edges of the belt fabric and each of said bent portions having its free end looped around an adjacent 15 cross wire or rod near the end of the latter and directly adjacent to a knuckled connection of a pair of the helically coiled wires.

The helically coiled wires may be of right or left hand twist as the case may be, and the ends 20 of the same at the marginal edges of the belt fabric are connected together by knuckling. Such knuckled portions are in offset relation with respect to each other at the opposite side or marginal edges of the belt fabric to accommodate the 25 positioning of the cross wires or rods, and the latter pass between the bights of the interconnecting helically coiled wires; the free straight ends of said cross wires or rods extending into the respective knuckled portions at the side or marginal edges of the belt fabric. The bends at the 30 opposite ends of the cross wires or rods may lie substantially at right angles to the longitudinal axis of the major portion of said cross wires or in an oblique direction, inclined slightly toward the 35 edge of the belt fabric, as may be desired.

The free ends of the helically coiled wires making up the belt may be knuckled together in the usual manner common in the manufacture of belts from helically coiled wires and the straight 40 ends of the cross wires or rods pass through these knuckled portions and terminate at the outer surfaces of the same. The bent ends of the cross wires or rods looped around the free straight ends of adjacent cross rods or wires lie within the 45 marginal edges of the belt fabric.

These and other features of my invention are more fully described hereinafter, reference being had to the accompanying drawing, more or less diagrammatic in character, in which:

50 Figure 1 is a plan view of a section of helically coiled wire belt fabric constructed in accordance with my invention.

Fig. 2 is a view of the edge of the fabric illustrated in Fig. 1, looking in the direction of the 55 arrow *a*, and

Fig. 3 is a sectional view on the line III—III, Fig. 1.

Referring to the drawing, Fig. 1 illustrates a section of belt fabric forming the subject of my invention, made up of a group of helically coiled 5 wires of the same twist in interconnected or interlaced relation. These wires may be of right hand twist or left hand twist, and in the present instance are shown as of right hand twist.

For convenience of description, these wires will 10 be numbered in pairs, indicated at 1 and 2, and these wires are shown as knuckled together at the side or marginal edges of the belt; the wires 1 and 2 of the first pair being shown as knuckled together at the left hand side of the belt, as indicated at 3, while at the right hand side of the belt, the wire 2 of the first pair and the wire 1 of the second pair are indicated as knuckled together at 4; an arrangement that is maintained throughout the full extent of the fabric. 20

The helices of the several wires provide the bights indicated at 1^a and 2^a at their interconnected or interlaced engaging portions and in these bights, transversely of the belt fabric, I place cross rods or wires 5 having bent ends which 25 may be disposed substantially at right angles to the major portion of the same. These ends, indicated at 5^a, are looped, as indicated at 5^b, around the opposite straight ends of adjacent cross rods or wires; the ends of said cross wires or rods 30 around which these bends are looped extending to and through the knuckled portions of the helically coiled wires as indicated at 5^c, and terminating at the side or marginal edges of the belt fabric. 35

The bent ends of the cross rods or wires lie with- 40 in the marginal edges of the belt fabric and by reason of their position they are prevented from displacement transversely of the belt fabric. The presence of these cross rods or wires materially strengthens the belt fabric and eliminates sub- 45 stantially all longitudinal stretch. By reason of the fact that the cross rods or wires are separately associated with the respective helically coiled wires there is no impairment in the flexibility of the belt, and at the same time the position of 45 the bent end of each cross wire or rod, which lies in engagement with a helix of one of the belt wires, holds the helically coiled wires from shifting transversely of the belt fabric on said cross rods or wires. 50

It will be understood, of course, that belt structures made up of my improved belt fabric may consist of sections of helically coiled wires of right hand twist alternating with sections of helically coiled wires of left hand twist throughout 55

the extent of the same; any suitable form of connection being employed to join the sections of belt fabric made up of the helically coiled wires of different twist, and that the improved form 5 of reinforcing rods or wires having bent ends which lie within the marginal edges of the belt fabric and in addition engage helices of the coiled wires with which they are associated to prevent said coiled wires shifting longitudinally of the 10 cross wires or rods, will be employed with said several belt sections.

The cross rods or wires with their ends previously bent may be set in place before the free 15 ends of the helically coiled wires are knuckled together, or said cross rods or wires may be positioned after this knuckling has been done and the free ends of the bent portions of said cross rods or wires put in the desired looped position with respect to the adjacent cross rods or wires 20 after they have been set in place; either arrangement being within the scope of my invention.

My invention comprises the use of simple and 25 easily arranged cross rods or wires which are positively retained within the belt fabric and which materially strengthen the same; cutting down, if not entirely eliminating, longitudinal stretch.

It will be understood of course, that modifications may be made in the construction and arrangement of my improved belt fabric without 30 departing from the spirit of my invention; all of which is deemed to be within the scope of the appended claims.

I claim:

1. Belt fabric made up of continuous helically 35 coiled wires in interengaging relation transversely of said fabric throughout their extent with the free ends of pairs of said wires knuckled together, and cross rods or wires passing through each set of interconnecting bights of said helically coiled 40 wires; each of said cross rods or wires having a bend at one end disposed within the knuckled connection of the helically coiled wires and terminating in looped connection with an adjacent cross rod or wire alternately at opposite edges of the fabric.

2. Belt fabric made up of continuous helically coiled wires in interengaging relation transversely of said fabric throughout their extent with the free ends of pairs of said wires knuckled together, and cross rods or wires passing through each set of interconnecting bights of said helically coiled wires; each of said cross rods or wires having a bend at one end wholly disposed within a knuckled connection at the margins of 55 the belt fabric and in engagement with helices of the coiled wires and terminating in looped connection with an adjacent cross rod or wire alternately at opposite edges of the fabric.

3. Belt fabric made up of helically coiled wires 60 in interengaging relation transversely of said fabric; said helically coiled wires having their free ends knuckled together in offset relation at opposite marginal edges of the belt fabric and cross rods or wires passing through each set of inter- 65 connecting bights of said helically coiled wires; each of said cross rods or wires having a bend at one end disposed within the helically coiled wires and lying in looped engagement with an adjacent cross rod or wire and the straight ends 70 of said cross rods or wires terminating within the knuckled connections of the helically coiled wires.

4. Belt fabric made up of helically coiled wires in interengaging relation transversely of said

fabric; said helically coiled wires having their free ends knuckled together in offset relation at opposite marginal edges of the belt fabric, and cross rods or wires passing through each set of interconnecting bights of said helically coiled 5 wires; each of said cross rods or wires having a bend at one end disposed within the margins of the belt fabric and in engagement with helices of the coiled wires and lying in looped engagement with an adjacent cross rod or wire alternately at opposite marginal edges of the belt fabric. 10

5. The method of making belt fabric of helically coiled wires with cross wire reinforcement, which comprises assembling a plurality of helically coiled wires in interconnected relation; placing cross rods or wires between each set 20 of bights of said helically coiled interconnecting wires; bending one end of each of said cross rods or wires into looped engagement with a straight portion of an adjacent cross rod or wire, and disposing said bent ends inwardly of the marginal 25 edges of the belt fabric.

6. The method of making belt fabric of helically coiled wires with cross wire reinforcement, which comprises assembling a plurality of helically coiled wires in interconnected relation; 30 placing cross rods or wires between each set of bights of said helically coiled interconnecting wires; bending one end of each of said cross rods or wires into looped engagement with a straight portion of an adjacent cross rod or wire, 35 and disposing said bent ends inwardly of the marginal edges of the belt fabric and in engagement with a helix of one of the coiled wires with which it is associated to maintain the position of said coiled wire thereon.

7. The method of making belt fabric of helically coiled wires with cross wire reinforcement, which comprises assembling a plurality of helically coiled wires in interconnected relation; knuckling pairs of the free ends of said helically 45 coiled wires; placing cross rods or wires between each set of bights of said helically coiled wires; bending one end of each of said cross rods or wires into looped engagement with a straight portion of an adjacent cross rod or wire; disposing 50 said bent ends inwardly of the marginal edge of the belt fabric and disposing the opposite straight ends of said cross rods or wires in the knuckled connections of said helically coiled wires.

8. The method of making belt fabric of helically coiled wires with cross wire reinforcement, which comprises assembling a plurality of helically coiled wires in interconnected relation; knuckling pairs of the free ends of said helically 60 coiled wires; placing cross rods or wires between each set of bights of said helically coiled wires; bending one end of each of said cross rods or wires into looped engagement with a straight portion of an adjacent cross rod or wire; disposing 65 said bent ends inwardly of the marginal edges of the belt fabric and in engagement with a helix of one of the coiled wires with which it is associated to maintain the position of said coiled wire thereon, and disposing the opposite straight 70 ends of said cross rods or wires in the knuckled connections of said helically coiled wires.

OTTO CARL SCHERFEL.
